UNITED STATES PATENT OFFICE

JESSE G. KING, OF DAYTON, OHIO, ASSIGNOR TO FRIGIDAIRE CORPORATION, OF DAYTON, OHIO, A CORPORATION OF DELAWARE

REFRIGERATING APPARATUS

Application filed May 30, 1928. Serial No. 281,607.

This invention relates to refrigerating apparatus and particularly to a novel form of refrigerating element or evaporator.

One of the objects of the invention is to provide an improved form of refrigerating element which is easily and cheaply constructed and one which is smooth, readily cleaned and of pleasing appearance.

More specifically it is an object of the invention to provide an improved form of evaporator, part of which may be readily coated by high-temperature processes and thereafter connected to the remaining uncoated portion in such a manner as to conceal the uncoated portion.

Further objects and advantages of the present invention will be apparent from the following description, reference being had to the accompanying drawing wherein a preferred form of embodiment of the present invention is clearly shown.

In the drawing:

Fig. 1 is a front elevation of the refrigerating cabinet containing an evaporator constructed in accordance with the present invention;

Fig. 2 is a side elevation of the refrigerating element;

Fig. 3 is an enlarged sectional view of a portion of the cabinet showing the refrigerating element in section;

Fig. 4 is an enlarged sectional view of a portion of the refrigerating element, and

Fig. 5 is an enlarged section on the line 5-5 of Fig. 3.

Evaporators of the type including a header or tank forming a reservoir for liquid refrigerant and depending loops of pipe connected to the header for enclosing an ice-making receptacle and for circulating refrigerant have been known heretofore and are exemplified by the patent to Osborn, No. 1,556,708, October 13, 1925. Objections to such evaporators are first, that they are very expensive to manufacture, second that they are difficult to clean, and third, that they are rather unsightly when placed in a refrigerator cabinet, and for the latter reason it has been customary to conceal the evaporators in refrigerator cabinets by a special lining or par-

tion. It has also been proposed to coat evaporators with vitreous enamel in order to provide a surface of pleasing appearance and one which is readily cleaned. It is essential to successful coating and baking of structures of this character that the thickness of the metal be substantially uniform in order to insure uniform heating and cooling of the structure thruout. On the other hand float controlled headers of the type shown by the Osborn patent referred to are so constructed of metal of such irregular thickness that it is impractical to enamel them. With these considerations in mind I provide a refrigerating element having an evaporating chamber 65 of sheet metal which may be readily enameled, and a separate header or tank forming a reservoir for liquid refrigerant and containing the float control mechanism, and secure these two devices together by a detachable coupling 70 after the evaporating chamber had been coated.

Referring to the drawing, 10 designates the usual header or tank adapted to contain a quantity of liquid refrigerant, provided with a removable head 11 upon which is supported an inlet connection 12 for liquid refrigerant, and outlet connection 13 for gaseous refrigerant, and a float control mechanism 14. A sheet of metal 15 is formed into a generally 80 rectangular enclosure as shown in Fig. 3, and is placed inside of a sheet 16 which is similarly formed. In addition, the sheet 16 is provided with vertical corrugations 17 which provide ducts 18 for circulating refrigerant and fins 19. The sheets 15 and 16 are welded together along their edges and the portions 17a between the corrugations of sheet 16 are spot welded to the sheet 15 in order to hold the sheets together against the pressure of 85 refrigerant within the ducts 18. The above ends of the ducts 18 are connected to two pipes 25 which are adapted to convey refrigerant to and from the ducts 18. In order that all of the ducts may communicate with the two pipes 25 the portions 17a of corrugations forming the individual ducts terminate below the pipes, the sheets 15 and 16 being spaced apart at the pipes, so that all of the 90 ducts are connected in parallel. At a suit- 100

able distance above the pipes 25 the sheets 15 and 16 are brought in contact with each other and are spot welded to close the refrigerant chamber formed by the ducts 18. Within the enclosure formed by the sheet 16 I place the tank 10 and connect this to each of the pipes 25 by means of detachable connections shown in Fig. 4. An upright pipe or nipple 30 is welded to the center of each pipe 25 and communicates with the pipe. The tank 10 has an opening thru which the nipple is inserted, and is provided with a boss 31 soldered or brazed to the tank around the opening. The boss 31 is recessed to receive a lead 15 gasket 32 which is confined between the sides of the boss and a shoulder 33 on the nipple 30. The nipple is externally threaded at its end in order to receive a nut 34 which clamps the tank to the nipple and effects the connection with the pipes 25. A suitable washer or other fluid tight packing 36 is interposed between the nut and the shell of the tank 10. The sheet 15 is provided with projections 40 adapted to support shelves 41 on which ice-making containers 42 may be placed. Lugs 43 are welded or otherwise suitably secured to the sheet 16 to receive bolts 44 by which the evaporator may be supported in the cabinet.

30 In constructing my improved evaporator I make the evaporating chamber formed by sheets 15 and 16 of material such as sheet steel and coat this with vitreous enamel in the usual manner. After the coating operation 35 the header or tank 10 is connected to the evaporating chamber as above described, the head 11 being removed to afford access to the interior of the tank while making the connections. After the connections have been 40 made, the head 11 is bolted to the tank in the usual manner and the evaporator is charged with refrigerant.

It will be noticed that the sheets 15 and 16 form an enclosure for the tank 10 and thus conceal it from view providing an evaporator whose exterior is completely covered with vitreous enamel. The evaporator as a whole is thus of a pleasing appearance, is readily cleaned and the difficulty of coating the complicated tank structure with vitreous enamel is avoided.

While the form of embodiment of the present invention as herein disclosed, constitutes a preferred form, it is to be understood that other forms might be adopted, all coming within the scope of the claims which follow.

What is claimed is as follows:

1. An evaporator for refrigerating apparatus comprising in combination a tank forming a reservoir for liquid refrigerant and a sheet metal evaporating chamber, said tank being disposed within the space defined by the inner wall of said chamber and removably connected together.

2. An evaporator for refrigerating apparatus comprising in combination a tank forming a reservoir for liquid refrigerant and sheet metal walls joined together to form an evaporating chamber, said walls enclosing said tank, and the tank and the chamber being removably connected together. 70

3. An evaporator for refrigerating apparatus comprising in combination means providing a tank forming a reservoir for liquid refrigerant and a hollow wall connected to the tank for circulating refrigerant, the wall including a pair of sheets and the inner one of said sheets entirely enclosing the tank. 75

4. An evaporator for refrigerating apparatus comprising in combination means providing a tank forming a reservoir for liquid refrigerant, and an evaporating chamber connected to the tank, said chamber including a pair of sheets forming a hollow wall, one of the sheets enclosing the tank. 80

5. An evaporator for refrigerating apparatus comprising in combination a tank forming a reservoir for liquid refrigerant and a hollow wall for circulating refrigerant enclosing said tank and detachably connected to the tank, said wall including a pair of sheets, one of the sheets being corrugated and the corrugations being secured to the other sheet to hold the sheets together against pressure within the wall. 90

6. An evaporator for refrigerating apparatus comprising in combination sheet metal walls forming an enclosure for ice-making receptacles, the walls including a pair of sheets spaced apart to provide a chamber for receiving refrigerant, a tank forming a reservoir for liquid refrigerant disposed within the enclosure and detachably connected to the chamber. 100

7. An evaporator for refrigerating apparatus comprising in combination, a tank forming a reservoir for liquid refrigerant, a hollow wall connected to the tank for circulating refrigerant, said wall including a pair of sheets formed to provide an enclosure, said tank being disposed within the upper portion of said enclosure. 110

8. An evaporator for refrigerating apparatus comprising in combination sheet metal walls forming an enclosure, the lower portion of said enclosure being adapted to receive ice making receptacles, the walls including a pair of sheets spaced apart to provide a chamber for receiving refrigerant, a tank forming a reservoir for liquid refrigerant disposed within the upper portion of said enclosure and detachably connected to the chamber. 115

9. An evaporator for refrigerating apparatus comprising in combination a tank forming a reservoir for liquid refrigerant and a hollow wall for circulating refrigerant enclosing said tank and detachably connected therewith, said wall including a pair of 120

130

sheets, one of the sheets being corrugated, said corrugations forming channels for directing air downwardly over the evaporator, the other of said sheets providing a smooth 5 interior surface on said hollow wall.

10. An evaporator for refrigerating apparatus comprising in combination, a tank forming a reservoir for liquid refrigerant, a flat hollow wall detachably connected to the 10 tank for circulating refrigerant, said wall including a pair of sheets formed to provide an enclosure, said tank being disposed within the upper portion of said enclosure.

15. In testimony whereof I hereto affix my signature.
